EXPANSIBLE LINK CHAIN FOR BRACELETS
OR THE LIKE

Samuel Meyerson, Brooklyn, N. Y.

Application April 24, 1951, Serial No. 14,937

Term of patent 14 years

(Cl. D45—4)

To all whom it may concern:

Be it known that I, Samuel Meyerson, a citizen of the United States States, residing in Brooklyn, county of Kings, State of New York, have invented a new, original, and ornamental Design for an Expansible Link Chain for Bracelets or the like, of which the following is a specification, reference being had to the accompanying drawing, forming part thereof, in which

Figure 1 is a top plan view of an expansible link chain embodying my new design, a portion of the center being broken away for convenience of illustration only;

The dominant feature of the design resides in the elements shown in full lines.

I claim:

The ornamental design for an expansible link chain for bracelets or the like, as shown and described.

SAMUEL MEYERSON.
